RAZOR BLADE CASE

Filed Dec. 15, 1928

FIG. I.

FIG. II.

FIG. III.

FIG. IV.

INVENTOR:

WILLIAM JOSEPH MANNING,

By *Arthur E. Raige*,
Attorney.

UNITED STATES PATENT OFFICE

WILLIAM JOSEPH MANNING, OF PHILADELPHIA, PENNSYLVANIA

RAZOR-BLADE CASE

Application filed December 15, 1928. Serial No. 326,189.

It is the object and effect of my invention, as indicated in Fig. I. Said holder 4 has in its most complex form, to provide a single receptacle in which may be compactly stored a supply of new safety razor blades, in their original envelop containers; a single razor blade in a holder which maintains oil in contact therewith; and a plurality of discarded dull blades; in such relation that any one may be instantly withdrawn from the casing independently of the others. However, in a simplified form of my invention, the case is adapted to receive only the holder for maintaining oil in contact with one or more blades.

My invention includes the various novel features of construction and arrangement hereinafter more definitely specified.

In said drawings; Fig. I is a perspective view of the complex form of my invention aforesaid, with the drawer in which the new and used blades are received, partly withdrawn to afford access to them.

Fig. II is a perspective view of the structure shown in Fig. I, but turned up side down with respect to that figure.

Fig. III is a separate perspective view of the blade oiling holder indicated in position in the case in Fig. I.

Fig. IV is a perspective view of the simpler modified form of my invention aforesaid.

Referring to Figs. I to III inclusive; the razor blade case comprises the outer shell 1 which is conveniently formed of a primarily plane piece of sheet metal bent to rectangular form. Said shell has the inwardly turned flange 2 at one end thereof of such extent as to cover the rear folded end or bight 3 of the blade oiling holder 4 which is conveniently formed of a cut strip of leather or leather substitute, having upon its inner face, a layer of felt 5. Said holder 4 is so far resilient that it tends to open upon its folded bight 3 as a hinge, to the position shown in Fig. III, and thus continually tends to separate itself from the blade inserted in it, but is normally held in contact with the blade when embraced in said outer shell 1, as shown in Figs. I and II. Said felt 5 is saturated with lubricating oil for contact with the safety razor blade 7 which is thrust between the free ends of said holder 4 and normally held in the casing 1

as indicated in Fig. I. Said holder 4 has notches 8 and 9 at its free ends aforesaid; said notch 9 being shallower than said notch 8 to facilitate the introduction of the blade 7 into said holder, and said notches are so proportioned as to expose the end perforation 10 thru the blade 7 so that it may be engaged by the thumb nail of the user to withdraw the blade; the outer case 1 being provided with the notch 12 corresponding with the notch 8 in said holder 4.

The drawer 14 is conveniently formed of a sheet metal stamping, to rectangular form, and is entirely open at the top, as indicated in Fig. II, to receive a plurality of new razor blades respectively held in their commercial envelop containers 15, as indicated in Fig. II.

What is the bottom wall of said drawer 14 in Fig. II is indicated at 16 in Fig. I and supports said holder 4 by frictional engagement therewith, in opposition to the outer wall of the case 1. It is to be particularly noted that said holder 4 is thus normally retained in its outer metallic shell 1 by said drawer 14 and serves to prevent accidental opening movement of the drawer; as the fact that it is a single piece folded causes it to continually tend to assume the form shown in Fig. III and thus frictionally engage both metallic walls between which it is embraced. Said drawer wall 16 has the blade inlet opening 17 thru which dull discarded blades 18 may be inserted for storage until such time as it is desired to have them resharpened. In order to prevent accidental escape of said dull blades 18, said opening 17 is located in such spaced relation with the end of the drawer 14 as to leave the inwardly turned flange 19 overhanging the ends of the blades 18 to such extent as to normally retain them. It is to be understood that said opening 17 is of such shape that a blade 18 may be inserted therein beyond the inner edge of said flange 19 and then slid backward beneath the latter to be retained.

Said opening 17 permits the finger of the operator to be inserted beneath the new blade envelops 15 indicated in Fig. II, so that the stack of envelops may be thus lifted to permit the user to withdraw the top one with greater

facility than if it was not thus raised. Of course, when it is not desired to either insert a dull blade or remove a new blade, the drawer 14 may be thrust into the casing until its end 5 wall 20, shown in Figs. I and II, is flush with said flange 9 of the case 1 to thus compactly store, in a single package, the three different classes of blades, to wit, a plurality of new blades in the envelops 15, a single blade 7 in 10 readiness for use, and a plurality of dull blades 18.

In the simple form of my invention shown in Fig. IV, a blade oiling holder 4, such as above described, is fitted in the case 21 which 15 is a rectangular shell conveniently formed of a primarily plane piece of sheet metal bent like the folder 4 but having flanges 22 and 23 at the opposite longitudinal edges of its wall 24 which are inwardly turned to hold the 20 opposite edges of its wall 25. The tab 27, which is punched from said wall 24, leaving the opening 28 in the latter, is perforated as indicated at 29, so that the entire structure shown in Fig. IV can be conveniently hung 25 upon a nail to normally retain a blade 30 in contact with the oil surface of said holder 4 and in readiness for instant withdrawal and use; such withdrawal being facilitated by providing the notch 31 in said wall 24 to 30 permit the user to engage his thumb nail in the end perforation 32 of said blade 30.

However, in both forms of my invention above described the oil absorbent blade holder is formed of a single piece of material which 35 is folded so that the blades are received in the bight thereof, and said absorbent material is of less area than the blade so that a portion thereof is exposed to be grasped by the operator to remove the blade, and those features of construction and arrangement may 40 be afforded by means other than the specific construction shown, which includes the notches 8 and 9 of different extent.

Altho I have shown said case 1 formed of 45 primarily plane sheet metal; it may be formed of a seamless rectangular tube cut to the length and shape indicated by a stamping operation, and, of course, the case 21 may be otherwise formed.

Therefore, I do not desire to limit myself 50 to the precise details of construction and arrangement herein set forth, as it is obvious that various modifications may be made therein without departing from the essential 55 features of my invention, as defined in the appended claims.

I claim:

1. A razor blade case, including an outer 60 metallic shell of substantially rectangular configuration; a blade holder fitted in said shell and including a single piece of flexible oil absorbent material, folded to receive a portion of a blade in its bight but continually tending to separate itself from said blade 65 when released; said absorbent material being

of less area than said blade, so as to continually expose a portion of the latter to be grasped by the operator.

2. A razor blade case as in claim 1, where- 70 in a drawer adapted to hold a plurality of razor blades is mounted to reciprocate in frictional engagement with said blade oil holder and adapted to normally maintain said holder in contact with a blade therein.

3. In a razor blade case, the combination 75 with an outer rectangular shell; of a drawer fitted to reciprocate in said shell; said drawer being open upon one side for insertion and removal of a commercial package of such blades; and having an inlet opening upon the opposite side thru which dull discarded 80 blades may be inserted independently of said commercial packages; said inlet opening being in such spaced relation to the end of the drawer as to afford an overhanging flange to 85 retain the discarded blades in said drawer.

4. A razor blade case as in claim 3, in which 90 the drawer is of less depth than said shell inclosing it, and the latter has an inwardly turned flange at one end thereof adapted to hold, in spaced relation with the side wall of 95 said shell, the wall of the drawer having said inlet opening; and a blade oiling holder is fitted in said case between the bottom of said drawer and the adjacent wall of said shell; whereby said drawer may be opened and shut without disturbing the blade in said oiling 100 holder, and said blade may be withdrawn and inserted without opening said drawer.

5. A receptacle for razor blades, comprising 105 a rectangular drawer having an inlet opening in the bottom thereof in spaced relation with the end of said drawer; whereby a series of new blades in commercial envelops 110 may be fitted in the upper portion of said drawer and dull discarded blades may be inserted thru said inlet opening in the bottom of said drawer, beneath the other blades; said inlet opening permitting the user to insert a finger at the bottom of said drawer to uplift its contents to afford ready access thereto at the top thereof.

6. A holder for a razor blade adapted to 115 maintain the latter oiled, including a folded flap of flexible material having an oil absorbent inner face, and continually tending to open upon its folded portion as a hinge to release said blade; and means embracing said folded material and normally maintaining it in contact with a blade inserted therein.

7. A structure as in claim 6, having notches 120 at its free ends affording access to the end of the blade inserted therein; one of said notches being deeper than the other to facilitate introduction of the blade.

In testimony whereof, I have hereunto signed my name at Philadelphia, Pennsylvania, this twelfth day of December, 1928.

WILLIAM JOSEPH MANNING.
